MOTORCYCLE FRAME

David S. Yetman, Marblehead, Mass., assignor to The Yetman Corporation, Beverly, Mass., a corporation of Massachusetts

Filed Jan. 7, 1966, Ser. No. 535

Term of patent 14 years

(Cl. D90—8)

FIG. 1

FIG. 1 is an oblique view of the motorcycle frame from the left side, showing my new design;

FIG. 2 is another view from the left side, slightly forward of the viewing position of FIG. 1;

FIG. 3 is another view of the left side, from below and from the rear.

The broken line disclosure in FIG. 1 is for illustrative purposes only.

I claim:

The ornamental design for a motorcycle frame, as shown and described.
